ATTORNEYS

UNITED STATES PATENT OFFICE.

ALBERT MCGALL, OF NEW YORK, N. Y., ASSIGNOR TO TUBAL CORPORATION, OF NEW YORK, N. Y., A CORPORATION OF NEW YORK.

SAFETY-RAZOR-BLADE SHARPENER.

1,353,485.

Specification of Letters Patent. Patented Sept. 21, 1920.

Application filed July 19, 1918, Serial No. 245,348. Renewed February 9, 1920. Serial No. 357,347.

To all whom it may concern:

Be it known that I, ALBERT MCGALL, a citizen of the United States, and a resident of New York, in the county of New York and State of New York, have invented certain new and useful Improvements in Safety-Razor-Blade Sharpeners, of which the following is a specification.

My invention relates to sharpeners for knives or safety razor blades or other keen-edged cutting instruments.

The object of my invention is the production of a sharpener of extreme simplicity of construction, of low cost to manufacture and which may be utilized to effectively and expeditiously sharpen the cutting edge of the blade it is desired to sharpen.

To the above ends my invention consists in the various parts and combinations of parts hereinafter more particularly described and then specified in the claims.

In the accompanying drawing:

Figure 1 is a front elevation of my improved sharpener.

Fig. 2 is a side elevation of the same.

Fig. 3 is a horizontal section of a modification of sharpener.

Referring more particularly to the several figures of the drawing:

1, 2 indicate the arms of my improved sharpener consisting preferably of two flat pieces of metal joined together at their lower ends by suitable rivets 3 or by other suitable means. The arms 1, 2 are provided adjacent their upper ends with circular openings 4 acting as seats for and adapted to receive the sharpening elements 5 which have curved meeting surfaces normally contacting with each other and which are held yieldingly together by the arms 1, 2 as illustrated. The sharpening elements 5 consist preferably of balls made of hard steel although the invention is not limited to any specific material of which the sharpening elements must be constructed nor is it limited to making them exactly spherical in shape as long as they have rounded meeting surfaces. 6 indicates the cutting edge of the razor blade 7 or other blade it is desired to sharpen. The cutting edge is sharpened in an obvious manner by merely drawing it between the sharpening elements 5 in the position indicated in Fig. 1. As is obvious inasmuch as

the sharpening elements are at all times yieldingly held together to permit them to be moved away from each other during the sharpening operation and inasmuch as there is a constant take-up therebetween, no special adjustment of their position is at any time necessary to accomplish the sharpening of the desired blade.

In the modification illustrated in Fig. 3, 8 indicates the body of a box having a cover 9 provided with a slot 10. The means for holding the sharpening elements 5 together in this case consists of a receptacle provided with a base 11 having vertical side arms 11' within which receptacle is provided elements 12 having circular openings adapted to receive the sharpening elements 5. The sharpening elements are yieldingly held together by means of the springs 13 interposed between and bearing against the side arms 11' and the elements 12 and to which side arms and elements they are preferably attached. To sharpen the blade, it is inserted in the slot 10 and the cutting edge drawn between the sharpening elements 5 in the same manner as in the preferred form of my invention.

What I claim as my invention is:—

1. A blade sharpener comprising sharpening elements having opposed curved surfaces and spring means for normally holding said sharpening elements in engagement with each other and adapted to permit said sharpening elements to be forced away from each other during the sharpening operation.

2. A blade sharpener comprising sharpening elements having opposed curved surfaces and means for normally holding said sharpening elements together with their curved surfaces in engagement with each other; said means being adapted to permit said sharpening elements to be forced away from each other and adapted also to permit a constant take-up between the sharpening elements during the sharpening operation.

3. A blade sharpener comprising spherical sharpening elements normally engaging each other and retaining means for said sharpening elements consisting of two strips of metal joined together and adapted to hold said sharpening elements yieldingly together.

4. A blade sharpener comprising spherical

sharpening elements normally engaging each other and retaining means for said sharpening elements consisting of two strips of metal joined together at the lower ends and 5 provided with circular openings adjacent their upper ends adapted to receive said sharpening elements, said retaining means being adapted to hold the sharpening elements in normal engagement with each other 10 and to permit a constant take-up between the

sharpening elements during the sharpening operation.

Signed at New York, in the county of New York and State of New York, this 18th day of July A. D. 1918.

ALBERT McGALL.
